(57) **CLAIM**

The ornamental design for a case for storing articles, as shown and described.

DESCRIPTION

FIG. 1 is a front, top perspective view of a case for storing articles, showing our new design;

FIG. 2 is a rear, bottom perspective view of the case for storing articles of FIG. 1;

FIG. 3 is a front elevational view of the case for storing articles of FIG. 1;

FIG. 4 is a rear elevational view of the case for storing articles of FIG. 1;

FIG. 5 is a right side elevational view of the case for storing articles of FIG. 1, the opposite left side elevational view being a mirror image thereof;

FIG. 6 is a top plan view of the case for storing articles of FIG. 1; and,

FIG. 7 is a bottom plan view of the case for storing articles of FIG. 1.

The broken lines in the drawings are included for purposes of illustrating portions of the case for storing articles that form no part of the claimed design.

1 Claim, 7 Drawing Sheets
